UNITED STATES PATENT OFFICE

2,656,924

SUPPORTING MEANS FOR A PORTABLE
SLUICE

William Thomas, Westwood, Calif.

Application October 25, 1948, Serial No. 56,303

1 Claim. (Cl. 209—508)

1

The present invention relates to portable wet or dry separation placer mining machine and it consists in the combinations, constructions and arrangements of parts herein described and claimed.

It is an object of the present invention to provide a placer mining machine which is entirely portable.

Another object of the invention is to provide an apparatus of the character set forth which includes a vibrating box which has novel means for the continuous separation of ordinary dirt from mineralized dust.

Another object of the invention is the provision of a novel accumulating trough which forms a part of the invention.

Another object of the invention is the provision of a sluice box forming a part of the invention and provided with novel means for angular adjustment thereof.

Another object of the invention is the provision of a novel arrangement of baffles in a sluice box forming a part of the invention.

Another object of the invention is the provision, in an apparatus of the character set forth, of an air pump for assisting in the removal of non-metallic dust particles.

A further object of the invention is the provision of a novel adjustable supporting means for a vibratory sluice box.

A still further object of the invention is the provision of, in an apparatus of the character set forth, novel means for the conservation of water in hydraulic mineral separation.

Another object of the invention is the provision of an apparatus of the character set forth which may be utilized as a prospecting apparatus as well as a commercial digger and separator.

Other and further objects of the invention will become apparent from a reading of the following specification taken in conjunction with the drawings, in which

Figure 1 is a side elevational view of an embodiment of the invention.

Figure 2 is a front elevational view thereof.

Figure 3 is a sectional view taken along line 3—3 of Figure 1.

Figure 4 is a fragmentary side elevational view, partly broken away, of a sluice box forming a part of the invention.

Figure 5 is a plan view of Figure 4.

Figure 6 is a sectional view taken along line 6—6 of Figure 5.

Figure 7 is a vertical sectional view of a vibrator box forming a part of the invention.

2

Figure 8 is a sectional view taken along line 8—8 of Figure 7.

Figure 9 is a sectional view taken along line 9—9 of Figure 7, and

Figure 10 is a perspective view, partly broken away, of an element of the invention.

Generally there is provided a portable wet or dry separation placer mining machine which includes some of the features and certain improvements over my United States Patent No. 2,405,622 and my copending application for United States Letters Patent bearing Serial No. 725,515. The present invention has a variety of uses. It may be utilized as a prospecting machine

moving from place to place engaged in sampling or it may be used as a stationary plant to which ores may be fed through the use of its own mechanisms. It briefly consists of a wheeled platform at one end of which is mounted an endless conveyor type digger which delivers to a vibrator box mounted to the rear thereof upon the platform. A removable accumulator box is provided in the lower end of the vibrator box and a removable plug is provided in one end of the accumulator for use in continuous operations. An endless conveyor has its lower end in the vibrator box and is supported at its upper end by a mast mounted upon the platform. The conveyor delivers to an angularly extending sluice box also supported by the mast in a novel and adjustable manner and air and water pumps are mounted upon the platform for uses hereinafter to be set forth. There is also provided an operator's cab at the other end of the platform and a power

plant is provided for operating the apparatus and for moving the vehicle. The apparatus may, if desired, secure its power from an outside source. Referring more particularly to the drawings, there is shown therein a portable placer mining machine comprising a chassis 10 having steering wheels 11 at the front end thereof and supporting wheels 12 adjacent the rear thereof. Upon the chassis 10 is a platform 13 at the front end of which is mounted a motor housing 14 and operator's cab 15.

The rear end of the platform is recessed and adjacent the recess is provided a pair of upright supporting members 16 in the upper ends of which is journaled a transversely extending shaft 17 to which is affixed a roller 18 over which an endless digger 19 is entrained.

The digger is provided with buckets 20 and is also entrained over a roller 21 carried by a shaft 22. The shaft 22 and the shaft 17 are interconnected by a pair of links 23 and hydraulic jacks

24 interconnect the links 23 and the members 16.

Immediately forwardly of the supporting members 16, there is pivotally mounted upon a transversely extending shaft 25 a vibrator box 26 having an upwardly extending portion 27 in which is located a plurality of perforated pipes 28 which are mounted at an angle in the box 26 and which extend downwardly through one side thereof to form connections 29. The pipes 28 form together what is known in the art as a "grizzly."

The body of the box 26 is provided with a vertically extending bulkhead 30 leaving a passage 31 between the top thereof and the portion 27 and a passage 32 between the bottom thereof and the bottom of the box 26.

The forward upper end of the box 26 is provided with an ear 33 which is interconnected by a link 34 to an eccentrically located position upon a wheel 35 which is, in turn, driven by a suitable source of power, preferably within the housing 14.

A mast 36 is centrally located upon the platform 13 and a sluice support 37 is revolvably mounted upon the upper end of the mast. A rearwardly extending boom 38 is pivotally mounted upon a pin 39 which extends upwardly from the support 37. The boom is provided with a pair of arms 40 through which transversely extends a shaft 41 which extends outwardly from one of the arms 40 and has mounted thereon pulleys 42 and 43.

The shaft 17 likewise extends outwardly and has a pulley 44 mounted on such extension. The pulleys 43 and 44 are interconnected by a belt 45 and the pulley 42 is connected by a belt 46 to a source of power such as a motor in the housing 14.

Upon the shaft 41 is mounted a roller 47 over which is entrained an endless conveyor belt 48 which is also entrained over a roller 49 mounted upon a shaft 50 which shaft is interconnected by a pair of links 51 with the shaft 41. The lower end of the belt lies within the box 26 upon the forward side of the bulkhead 30 and the belt is provided with a series of buckets 52. Links 53 interconnect the sides of the links 51 with the sides of the chassis 13.

The support 37 is provided with a rearwardly extending shelf 54 having mounted thereon a motor 55 whose shaft 56 is interconnected with a wheel 57 by means of a belt 58. Eccentrically connected with the wheel is one end of a link 59 the other end of which is connected to a dependent ear 60 carried by the rearward end of a sluice 61 which extends downwardly and forwardly and which is provided with a pair of dependant lugs 62 at its center of gravity.

A collar 63 is affixed to the mast 36 and is interconnected with the lugs 62 by means of an hydraulic jack 64. Outwardly extending from the sluice 61 at points adjacent the rear end thereof is a pair of pins 65 which lie within vertical slots 66 formed in the sides of the support 37. The sluice 61 is provided with a plurality of spaced, inverted L-shaped transversely extending baffles 67 along its bottom of which is laid a series of spaced longitudinally extending inverted V-shaped members 68.

Between the mast 36 and the cab 15 there is provided an air pump 69 and a water pump 70.

The lower end of the vibrator box 26 is provided with a collector box 71 which is generally rectangular in cross section and which is provided with an elongated slot 72 in its upper side and which extends transversely of the box 26.

The bottom 73 of the box 71 slopes downwardly toward one end thereof which is provided with a removable plug 74.

In operation, it will be apparent that the apparatus may be moved from place to place in the conventional manner of a truck or other motor vehicle and that the digger 19 may be engaged with either virgin ore or with ore which has been accumulated for the purpose. The digger may be moved forwardly and rearwardly by means of the jack 24 and its buckets 20 will deliver ore to the extended portion 27 of the vibrator box 26 whereupon the grizzly pipes 28 will operate to spray water into the incoming ore. It is to be understood that the connections 29 will be supplied with water from the water pump 70 through connections not shown. The thus wetted ore is thoroughly agitated within the box 26 through the motion of the link 34 and its attendant mechanism and in the course of such agitation the gold bearing particles will settle to the bottom of the box 26 and pass through the slot 72 into the collector box 71. During continuous operation of the apparatus, the plug 74 may be removed and a constant stream of metallic bearing ore may be collected from the unplugged opening. It will be seen that the lower end of the conveyor 48 lies within the forward portion of the agitator box and forwardly of the bulkhead 30.

It will also be understood that the conveyor 48 is designed to remove dirt from the box 26 at a greater rate than the same is delivered thereto by the digger 19. Hence, the conveyor 48 will remove the lighter portions of the ore, that is to say that ore from which the metal bearing portion has been removed by agitation as it passes through the passage 31. It will also remove that portion of the ore rising from the passage 32. The conveyor 48 delivers its load to the rearward end of the sluice 61 which is agitated by the link 59 and its attendant mechanisms. It will be seen that the angle at which the sluice 61 lies may be regulated by the hydraulic jack 64 and that, regardless of the position of the sluice 61 the pins 65 are enabled to reciprocate in the slots 66. It will also be seen that the sluice may be revolved upon the mast 36 to any convenient position. If the apparatus is used without water the air pump 69 may be used to direct blasts of air through suitable hose connections at convenient places upon the sluice 61 to remove dust therefrom. In this case the baffles 67 and 68 may be removed from the sluice. It will also be understood that water may be collected from the sluice and reused by the pump 70 in localities where there is a scarcity of water.

While but one form of the invention has been shown and described herein, it will be readily apparent to those skilled in the art that many minor modifications may be made without departing from the spirit of the invention or the scope of the appended claim.

What is claimed is:

An apparatus of the character described comprising a platform, a mast centrally mounted upon the platform, a sluice support revolvably mounted upon the upper end of said mast and having a central vertically extending passage therethrough and having a vertically extending slot in each side thereof communicating with said passage, an elongated sluice extending through said supporting sluice, a guide pin extending laterally from each side of said sluice adjacent the inner end thereof and each positioned in one of said slots, a platform affixed to said

sluice support, a motor mounted on said platform, a wheel connected to the motor, a link having one end eccentrically connected to the wheel and having its other end connected to the inner end of said sluice, a dog affixed to the bottom of the sluice at approximately its center of gravity, a collar affixed to the mast, and a jack interconnecting said collar and said dog.

WILLIAM THOMAS.
